UNITED STATES PATENT OFFICE.

GEORGE E. SAVAGE, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A WAFFLE IRON OR SIMILAR ARTICLE.

Application filed October 21, 1922. Serial No. 4,052. Term of patent 7 years.

To all whom it may concern:

Be it known that I, GEORGE E. SAVAGE, a citizen of the United States, residing at Meriden, in the county of New Haven and State of Connecticut, have invented a new, original, and ornamental Design for a Waffle Iron or Similar Article, of which the following is a specification, reference being had to the accompanying drawing, forming a part thereof.

Figure 1 is a side elevation of a waffle iron showing my new design; and Fig. 2 is a plan view of the same.

I claim:

The ornamental design for a waffle iron or similar article as shown.

GEO. E. SAVAGE.
